UNITED STATES PATENT OFFICE.

THEODORE VARNEY, OF PITTSBURGH, PENNSYLVANIA, ASSIGNOR TO WESTINGHOUSE ELECTRIC AND MANUFACTURING COMPANY, A CORPORATION OF PENNSYLVANIA.

ELECTRIC-LINE SUPPORT.

1,138,702.

Specification of Letters Patent.

Patented May 11, 1915.

Application filed December 2, 1908. Serial No. 531,057.

To all whom it may concern:

Be it known that I, THEODORE VARNEY, a citizen of the United States, and a resident of Pittsburgh, in the county of Allegheny and State of Pennsylvania, have invented a new and useful Improvement in Electric-Line Supports, of which the following is a specification.

My invention relates to supporting structures for electric line conductors, and particularly to insulating supports for high-voltage electric railway trolley line conductors.

The object of my invention is to provide a simple and durable structure of the class above indicated, in which a novel and particularly advantageous form of insulator may be employed.

In the catenary form of line structure which is usually employed for high-voltage railway service, a pin is adjustably mounted on a horizontal arm or bracket and a high-voltage insulator is mounted on the pin to serve as a direct support for a messenger wire or cable. In order to obtain the necessary strength, a metal pin is usually employed and, consequently, a maximum electrical strain is imposed upon the insulation between the top of the pin and the wire, which is likely to cause a break-down at that point.

According to my present invention, I provide an insulator of the skirt type having a downwardly projecting corrugated end which is secured to a metal block or base. The metal base may be secured, in any suitable way, to a bracket arm or other supporting structure but, in order that the insulator, which is ordinarily composed of porcelain, may be subjected to compression strains only, I provide an interposed bracket which is substantially semi-circular in form and upon which the insulator is adjustably supported in such a manner that its axis may always be radial thereto. The bracket is adjustably mounted on a bracket arm or other suitable supporting structure.

When my supporting structure is employed on a straight stretch of electric line, the axis of the insulator is substantially vertical, but, when it is used on curves, the insulator is adjusted upon the curved bracket until its axis is oblique in order to best oppose the pull exerted by the wire at such point.

My invention is illustrated in the accompanying drawings in which—

Figure 1 is an elevation of a line support constructed in accordance therewith. Fig. 2 is a partially sectional view, on a larger scale, of the insulator and the curved bracket of Fig. 1, and Figs. 3 and 4, are respectively, sectional views on the lines III—III and IV—IV of Fig. 2. Fig. 5 is a view corresponding to Fig. 2, but disclosing a modified insulator that may be found preferable for some classes of service. Fig. 6 is a detail view of an insulator which may be substituted for that shown in Fig. 5.

Referring to Figs. 1, 2, 3 and 4 of the drawings, the structure here shown comprises a horizontal arm 1 which is secured to a pole 2 or other upright support, an insulator 3 and a curved bracket 4 which is adjustably supported on the arm 1. The bracket 4 is substantially semi-circular in form and is adjustably supported on the arm 1 by means of J-bolts 5 which coöperate with hook projections 6, as shown in Fig. 3 of the drawings, to grip the arm 1 which is preferably of T or I-shape, in cross section. The insulator 3 has the general form of a skirt type line insulator, but, instead of being hollow, it is solid and is provided with a corrugated cylindrical end 6^a which projects axially downward and is connected in a recess 7, with which a metal block or base 8 is provided. The member 8 is provided with a projection 9 of hook shape and is adjustably supported upon the bracket 4 by means of a J-bolt 10 which coöperates with the projection 9 to grip the bracket 4, as shown in Fig. 4 of the drawings, the bracket being preferably of T or I-shape in cross-section. By loosening the nut 11, which clamps the insulator base 8 to the bracket 4, the insulator may be adjusted along the inner cylindrical surface of the bracket, the arrangement of parts being such that the axis of the insulator is always radial with reference to the bracket. It is evident that the bracket may be adjusted along the arm 1 and secured to it at any suitable point. The form of the bracket 4 is such that it serves as a guard for the insulator and also catches the conductor in case the insulator is broken. The form of the insulator may, of course, be varied, but, for high-voltage service, the creepage distance between the conductor and the base should be relatively great. Since

the insulator is not recessed to receive the supporting pin, it is unusually strong, and, therefore it is not likely to be seriously injured. This is particularly true since the 5 operating mechanical strains to which it is subjected are applied in compression, as hereinbefore pointed out.

When electric trolley wires are suspended over tracks on which both steam and electric vehicles operate, insulators of the form shown in Fig. 2 tend to become coated with soot or other foreign particles, which detract from their insulating properties, and, therefore, in such case, it is desirable to employ insulators of simple outline, like or similar to that shown in Figs. 5 and 6, to which reference may now be had. As here shown, the insulator is in the form of a sleeve or tube and is secured at the base 8 by a bolt 12 which extends laterally through its end and is set in cement. The upper end of the insulating tube is provided with a cap 13 having projections 14 for gripping the messenger wire or cable. The outer 25 surface of the tube may be either smooth, as indicated in Fig. 5, or corrugated, as shown in Fig. 6, provided its outline is such that soot and dirt will be washed off by the rain.

While the structures illustrated are considered particularly desirable, they may obviously be considerably modified without departing from the spirit of my invention and I desire that only such limitations shall be imposed as are indicated in the appended 35 claims.

I claim as my invention:

1. A supporting means for an electric conductor comprising a bracket having a curved supporting portion, a metal base block having an open-top recess, means for clamping said block adjustably to the curved portion of said bracket, and an upwardly projecting insulator having its lower end cemented into the recess in said block and provided 45 with means for attaching a wire or cable to its upper end.

2. A supporting means for an electric line conductor comprising a bracket having a curved supporting portion, a metal base block having an open-top recess and a bottom clamping bolt to engage the curved portion of said bracket, and an upwardly projecting insulator having its lower end ce-

mented into the recess in the block and provided with means for attaching a wire or 55 cable to its upper end.

3. An insulating support for an electric line conductor comprising a bracket having a curved supporting portion, a metal base block rigidly clamped upon said curved supporting portion but adjustable along the same when the clamping means is loosened, and an insulator secured to the base block and having its axis radial to the bracket. 60

4. An insulating support for an electric 65 line conductor comprising a bracket having a curved supporting portion, a metal base block adjustably mounted on said supporting portion, and a solid insulator secured to the base block and projecting radially inward toward the center of curvature of the bracket. 70

5. A supporting structure for an electric line conductor comprising a substantially horizontal member, a bracket having a 75 curved supporting portion and provided with means for adjustably clamping it to said member, a metal base block adjustably secured to the supporting portion of the bracket, and an insulator secured to the base 80 block and projecting radially inward toward the axis of curvature of the bracket.

6. A supporting structure for an electric line conductor comprising a substantially horizontal arm, a bracket adjustably secured 85 thereto and having a curved supporting portion, and an insulator comprising a metal base block adjustably mounted upon the inner surface of the curved portion of the bracket and a porcelain block having a 90 groove at its outer end to receive the line conductor and a corrugated cylindrical portion projecting radially inward, said metal base block being recessed to receive the corrugated portion of the porcelain block, 95 whereby the insulator may be so adjusted that the strains due to the tension in the conductor may be exerted upon the insulator in an axial direction.

In testimony whereof, I have hereunto 100 subscribed my name this 27th day of Nov., 1909.

THEODORE VARNEY.
